W. HEILEMANN & H. KANONENBERG.
PIVOT STAND FOR WHEELED GUN CARRIAGES.
APPLICATION FILED APR. 26, 1913.

1,120,483.

Patented Dec. 8, 1914.

Fig. 1.

UNITED STATES PATENT OFFICE.

WALTER HEILEMANN AND HEINRICH KANONENBERG, OF ESSEN-ON-THE-RUHR, GERMANY, ASSIGNORS TO FRIED. KRUPP AKTIENGESELLSCHAFT, OF ESSEN-ON-THE-RUHR, GERMANY.

PIVOT-STAND FOR WHEELED GUN-CARRIAGES.

1,120,483.

Specification of Letters Patent.

Patented Dec. 8, 1914.

Application filed April 26, 1913. Serial No. 763,845.

To all whom it may concern:

Be it known that we, WALTER HEILEMANN, residing at 22 Otmarstrasse, Essen-on-the-Ruhr, Germany, and HEINRICH KANONENBERG, residing at 99 Rellinghauserstrasse, Essen-on-the-Ruhr, Germany, both subjects of the Emperor of Germany, have invented a certain new and useful Improvement in Pivot-Stands for Wheeled Gun-Carriages, of which the following is a specification.

The subject matter of the present invention resides in a pivot stand for wheeled gun carriages, which is constructed so that it does not need to be tilted, when the height of the trail end changes during swinging around of the gun carriage.

In the accompanying drawing is shown one embodiment of the invention and Figure 1 shows a side elevation of the pivot stand together with a gun carriage, Fig. 2 a top plan view of the pivot stand, and Fig. 3 a section of the pivot stand along lines 3-3 of Fig. 1 seen from the left.

The pivot stand has a pedestal A and an upper portion, which consists of two parts B and B¹, to be described later. The pedestal A may be let into the ground and is provided with a bearing a¹ for the pivot proper b² of the part B. Between this part and the pedestal A is inserted a ball bearing a². Two transverse bearings b³ see Figs. 1 and 3 are provided on the part B¹ for the axle-tree G of the gun carriage. The bearings b³ are open on the side nearest the muzzle of the gun, see Fig. 1, and may be closed by caps b⁴. The height of the pivot stand has been selected so that the wheels D of the gun carriage do not touch the ground when the axle-tree G rests in the bearings b³ b⁴.

A ring R is revolvably but non-displaceably mounted in an annular groove a³ of the pedestal A, which ring is composed of two parts. On this ring are provided two trunnions r¹, situated diametrically opposite each other and on which a fork E is mounted to oscillate, and which fork carries a sleeve with an eyelet e¹. This eyelet is intended to engage with a hook f¹, on the trail body F of the gun carriage. The fork E is provided for the purpose of directly transferring to the pedestal A the recoil pull caused by the shot, and thereby preventing the tilting of

the pivot stand under the action of the recoil pull.

The part B¹ of the pivot stand is carried in the part B, by means of two flanges b⁵ which engage under flanges b⁶ of the part B, see for instance Fig. 3, in such a manner that it may be displaced relative to the part B at right angles to the axis of the bearings b³ b⁴, that is in the length direction of the gun carriage resting on the pivot stand. During transport of the pivot stand, the parts B and B¹ may be coupled together, as for instance by means of a detachable key bolt C, see Figs. 1 and 2.

When the gun is to be used for firing against rapidly moving targets (for instance air ships) it is brought upon the pivot stand. For this purpose the pedestal A is let into the ground and the gun carriage is rolled up on wedges, see Fig. 1, which are laid along the pedestal until the axle-tree G rests in the bearings b³. The bearings b³ are thereupon closed by means of the caps b⁴, the key bolt C taken out, and the eyelet e¹ of the fork E is brought into engagement with the hook f¹ of the trail body. The gun carriage may thereupon be swung easily, around the axis of the pivot b², by means of a training gear (not shown in the drawing), which is inserted between the pedestal A and the part B; or by means of a hand spike K, see Fig. 1. The ring R will then turn in the groove a³.

Should the trail end during the training of the gun carriage be lifted by means of the hand spike and then again laid down on the ground, or should the trail slide on uneven ground during the training of the gun carriage the fork E will then rock around the axis of the trunnions r¹ and the axle-tree G will oscillate in the bearings b³ b⁴. A displacement of the part B¹ of the pivot stand relative to the part B will simultaneously take place without tilting the pivot stand.

The described displacement is caused by the raising and lowering of the point f² of the trail body where the fork E is engaged by the hook f¹ and this point travels in a circular arc α - α described from the axis of the trunnions r¹, the distance of this point f² from the axle-tree remaining constant.

As the pivot stand in consequence of the described construction does not need to be

tilted during the training of the gun carriage, this training of the gun carriage may take place with the least possible power consumption. The described arrangement moreover possesses the advantage that the trail end of the gun carriage, even on rough ground, can rest on the ground in any position of the gun carriage.

We claim:—

- 10 1. A pivot stand for a wheeled gun carriage having a trail comprising a pedestal, a pivot mounted to revolve on said pedestal, a cradle constructed to engage with and support the forward end of the gun carriage; said cradle and pivot having interengaging sliding members permitting displacement of the cradle relative to said pivot.
- 15 2. A pivot stand for a wheeled gun carriage having a trail comprising a pedestal, a pivot mounted to revolve in said pedestal, a cradle constructed to engage with and support the forward end of the gun carriage; said cradle and pivot having interengaging sliding members permitting displacement of the cradle relative to said pivot in the longitudinal direction of the gun carriage.
- 20 3. A pivot stand for a wheeled gun carriage having a trail and an axle-tree, comprising a pedestal, a pivot mounted to revolve in said pedestal, a cradle mounted on said pivot, a pair of transverse bearings on said cradle adapted to receive the axle-tree of the carriage, said cradle being adapted to slide on said pivot in the longitudinal direction of the gun.
- 25 4. A pivot stand for a wheeled gun carriage having a trail and an axle-tree; comprising a pedestal, a pivot mounted to re-
- 30 5. A pivot stand for wheeled gun carriages having a trail and an axle-tree, comprising a pedestal, a pivot mounted to revolve in said pedestal, a cradle mounted on said pivot to slide thereon in the longitudinal direction of the gun, a pair of transverse bearings on said cradle adapted to receive the axle-tree of the gun carriage; a trunnion ring mounted to revolve in a horizontal groove in said pedestal, a pair of diametrically opposite trunnions on said ring, a fork engaging said trunnion to oscillate thereon; an eyelet on said fork and a hook on the trail for engaging said eyelet; whereby the gun carriage may be swung in a horizontal plane around the axis of said pivot.
- 35 6. A pivot stand for wheeled gun carriages having a trail and an axle-tree, comprising a pedestal, a pivot mounted to revolve in said pedestal, a cradle mounted on said pivot to slide thereon in the longitudinal direction of the gun, a pair of transverse bearings on said cradle adapted to receive the axle-tree of the gun carriage; a trunnion ring mounted to revolve in a horizontal groove in said pedestal, a pair of diametrically opposite trunnions on said ring, a fork engaging said trunnions to oscillate thereon, and an eyelet on said fork, a hook on the trail for engaging said eyelet; whereby on raising the trail end from the ground the axle-tree will rock in the cradle bearings and the cradle slide on the pedestal.

The foregoing specification signed at Dusseldorf, Germany, this 5th day of April, 1913.

WALTER HEILEMANN. [L. S.]
HEINRICH KANONENBERG. [L. S.]
